UNITED STATES PATENT OFFICE.

GUSTAVE O. SAUERMANN, OF KENESAW, NEBRASKA.

AUTOMATICALLY-OPERATED DOOR.

1,269,962.

Specification of Letters Patent. Patented June 18, 1918.

Application filed June 15, 1915. Serial No. 34,279.

To all whom it may concern:

Be it known that I, GUSTAVE O. SAUERMANN, citizen of the United States, residing at Kenesaw, in the county of Adams 5 and State of Nebraska, have invented certain new and useful Improvements in Automatically-Operated Doors, of which the following is a specification.

This invention relates to doors and more 10 particularly to an improved means for automatically opening and closing a sliding door.

The object of this invention is to provide 15 a door opening means that is preferably arranged in the path of travel of live stock and includes a pair of pivotally connected platforms that, by the weight of an animal thereon the door will be opened and after 20 the animal has passed off of the platform, the door will be closed.

Another object of this invention is to provide 25 an automatically operated door including a pair of platforms, the same being so constructed as to provide no openings or crevices into which animals are liable to place their feet.

A still further object of this invention is 30 to provide a device that is simple in construction, efficient in operation, and consists of a minimum number of parts.

With these and other objects in view, this 35 invention consists of certain novel features of construction, combination and arrangement of parts, as will be hereinafter more fully described and claimed, and shown in the accompanying drawings wherein:—

Figure 1 is a longitudinal section view 40 of the improved device;

Fig. 2 is a section taken on line 2—2 of Fig. 1;

Fig. 3 is an enlarged view in elevation of one of the sheaves used with this device;

Fig. 4 is a section taken on line 4—4 of Fig. 1.

Referring to the parts by reference numerals, a pair of uprights are designated by the numeral 10, each having a groove 11 formed therein into which the ends of the door 12 are positioned and the same are 50 slidable therein. A supporting means for a pair of platforms used to open this door is designated in its entirety by the numeral 13 and the platforms 14 and 15 are movably connected to this supporting means 13. 55 Blocks 16 are secured at one end of the sup-

porting means 13 and the supporting joists 17 of the platform 14 have offset ends 18 through which the pins 19 are passed to pivotally secure the platform 14 to the block 16. Pulley wheels 20 are carried by the support 13 and the supporting joists 21 of the platform 15 have offset ends 22, the said ends 22 being in engagement with the pulley wheels 20 to facilitate the movement of the platform 15. Intermediate the blocks 60 16 and the pulley wheels 20 is a sill 23, the same having an inclined face 24 that is adapted to receive the platforms 14 and 15, when the same are in their lowered position. These platforms 14 and 15 are pivotally secured by the rod 26 passing through the overlapping ends of the joists 17 and 21 and, therefore, movement of one of the platforms will obviously move the other. The abutting ends of the platforms 14 and 70 15 are so made as to form the substantially concavo-convex joint, the ends of the platform being indicated by the numeral 27 and the abutting portion of the support made to conform to the curvature of the end of the 80 platform, designated by the numeral 28 and by this arrangement regardless of the position of the platforms relative to the support 13, the same will always be in engagement and no opening or crevice will be had 85 between the same.

Brackets 29 are secured to the uprights 10 and journaled therein, is a shaft 30, the same having thereon a pair of spirally arranged sheaves 31. Over these sheaves 31 90 are trained cables 32 having one of their ends in connection with the door 12, as indicated by the numeral 33 and at the opposite ends thereof are positioned weights 34. Secured to the shaft 30 are platform connecting cables 35 that are secured about the opposite extremities of the shaft and passed through the openings 36 in the support 13 and are in connection with the joists 17 of the platform 14. 100

The operation of this device is as follows:

An animal treading on the platform 15 will, by its weight, move the said platform downwardly and the same being pivotally connected with the platform 14 will likewise move the platform 14 downwardly until the same are in engagement with the sill 23. It being obvious that the platform 14 is pivotally secured to the support means 13 and the platform 15 is capable of move- 110

ment relative to the support means 13 in that the offset ends 22 of the joints 21 are positioned on the pulley wheels 20. As the platforms are moved to a position as above 5 set forth, the cables 36 will rotate the shaft 30 and move the door 12 to an open position by means of the cable 32 being trained over the spirally arranged sheaves 31. It is to be noted that the weights 34 are so arranged 10 as to facilitate the rotation of the sheaves 31 and obviously the raising of the door. After the device has been positioned as has been heretofore set forth and the animal passes through the uprights 10, the door 15 is of such weight as to move the platform to the position as shown in Figs. 1 and 2 and, the same by gravity follows to the position as shown in Figs. 1 and 2. If so desired means can be provided on the standard 20 10 whereby the door 12 can be held in its open position.

It is obvious that minor changes may be made in the form and construction of this device without departing from the material 25 parts thereof. It is, therefore, not wished to confine the construction to the exact form herein described and claimed but it is wished to include all such as properly come within the scope claimed.

30 What is claimed is:—

1. In a device of the kind described, a pair of standards, a door slidable in said standards, a support, a pair of hingedly secured platform sections in connection with 35 said support, the abutting edges of said support and said platform sections being rounded so that when the platform sections are moved the rounded edges will be in engagement with each other, a rotatable shaft carried by said supports having a pair of 40 sheaves mounted thereon, cables connected at one end to the door and trained over the respective sheaves, counterweights connected to the other end of the cables, means opera-

tively connecting said platform sections 45 with said shaft whereby when a weight depresses said platform sections, the shaft will be rotated to raise the door, said door closing by gravity and raising the platform sections when the weight is removed. 50

2. In combination, a vertically sliding door, a shaft above the door, a cable attached at one end to the door and passing around the shaft, a counterweight at the other end of the cable, a platform section at 55 each side of the door, the two sections being hinged at their inner ends, and a cable having an end attached to the shaft and wound thereon, and having its opposite end connected with one of the platform sections, 60 whereby when a weight depresses either platform section, the door slides upwardly into open position, said door closing by gravity and raising the platform sections when the weight is removed. 65

3. In combination, a vertically sliding door, a shaft above the door, a spiral sheave pulley on the shaft, a cable attached at one end to the door and having its opposite end passing around the spiral sheave pulley, a 70 counterweight at the other end of the cable, a platform section at each side of the door, the two sections being hinged at their inner ends, and a cable having an end attached to the shaft and wound thereon, and having its 75 opposite end connected with one of the platform sections, whereby when a weight depresses either platform section, the door slides upwardly into open position, said door closing by gravity and raising the platform sections when the weight is removed. 80

In testimony whereof I affix my signature in presence of two witnesses.

GUSTAVE O. SAUERMANN.
